TRANSPOSING DEVICE FOR PIANO
ACCORDIONS

Frank Kostka, Buffalo, N. Y.

Application February 6, 1937, Serial No. 124,448

3 Claims. (Cl. 84—376)

This invention relates generally to certain new and useful improvements in musical instruments, but more particularly to a transposing device for accordions and the like.

5 One of the objects of my invention is to provide a simple and convenient mechanism whereby the player of a piano accordion or like instrument may easily and accurately effect a key transposition, thereby increasing the musical 10 range and capacity of tone production of such instruments to a much greater degree than is possible without such mechanism.

Other objects of my invention will be set forth in the following description and drawings which 15 illustrate a preferred embodiment thereof, it being understood that I may make such changes as I may deem necessary from time to time without departing from the spirit of my invention.

20 Figure 1 is a perspective view of a piano accordion embodying my invention. Figure 2 is a transverse vertical section taken on the line 2—2, Figure 1. Figures 3 and 4 are fragmentary horizontal sections taken substantially on the correspondingly-numbered lines in Figure 2. Figure 5 is a fragmentary bottom plan view, partly in section, of the reed-frame unit and associated parts.

Like characters of reference indicate corresponding parts in the different views.

For many reasons it is desirable that transposition of key be made available to a player on such a musical instrument without the necessity for his having to make such transposition mentally. For instance, an accordion player might wish to play a duet with a piano, the pitch of which is slightly higher or lower than that of his accordion. If such player were very skilled he might be able to make the necessary transposition by means of his mental ability. My invention relieves him from such a necessity. By its operation as hereinafter described, the unskilled as well as the skilled can secure an alteration to a higher or lower key and still play from the written music as originally written.

Referring now to the drawings, the instrument generally comprises a treble side 10 having the usual keys 11, a bass side 12, and a bellows 13.

50 The standard reed carrier of the treble side of the piano accordion consists of a case or frame 14 of wood or other suitable material containing four reed boxes or chambered blocks 15, each block having a series of openings 16 and a second series of companion openings 17. The reeds 18 are associated with corresponding companion pairs of openings 16 and 17 and the keys 11 are connected to companion valves 19 of the usual type and each of such valves controls the supply 55 of air to one or more reeds. In the drawings,

each valve is shown as controlling companion openings 16, 17 of a pair of adjoining reed blocks.

My device necessitates for its successful operation a re-arrangement of the reeds from the standard arrangement. To this end, the reed blocks 15 are attached in their usual spaced, parallel relation to adjustable frames or yokes 20, 21 adapted to move lengthwise within the case 14. These frames are secured adjacent the ends of the several reed blocks to tie them as a 10 complete unit, the frame 20 extending over the ends of the reed blocks and terminating at its opposite ends in guide arms 22 guided on suitable tracks or ways 23 secured to the opposing side walls of the case 14. The companion tie-frame 15 21 extends over the bottom sides of the reed blocks and have similar guide arms 24 guided on like tracks 25. By this tie-frame and guiding structure, the reed blocks are effectually and positively held as a complete unit against lateral 20 motion and vibration to assure their longitudinal 25 adjustment when desired in accordance with my invention. For a purpose which will herein-after appear, the reed blocks are of a length to provide for additional reeds over those normally used, each reed block having an extra or additional reed at each end thereof, such reeds being indicated at 18^a and 18^b, respectively, and being adapted, at different positions of adjustment of the reed blocks, to register or not register 30 with the companion endmost openings 16, 17.

The longitudinal adjustment of the reed-frame unit is effected by means of a screw 26 supported at its knobbed end 27 in the end wall of the case 14 while its threaded end engages an internally-threaded collar or nut 28 applied to the adjoining reed-carrying frame 20. The rotation of this screw by the operator causes the reed frame unit to slide longitudinally in the case, thereby altering the relation between the respective reeds 18 and the valves 19 to thereby effect 40 the desired transposition.

By preference, a dial 29 is located at the same end of the case 14 as the screw 26, and traversing this dial is a pointer 30 operatively connected by 45 a reduction gear train 31 to the adjusting screw, as shown in Figures 2, 3 and 5, permitting the operator to see at a glance the amount of rotation needed to bring the reed frame to position for the pitch or key desired.

50 As heretofore explained, the depression by the player of the player-keys actuates through intermediate levers the raising of the valves 19 and the consequent production of tones through the reeds below. These valves are arranged in two 55 parallel rows as shown in Figures 1 and 2, each row of valves controlling companion pairs of openings 16, 17, and associated reeds 18.

The exact relationship between the player keys, the actuating levers and the valves to the notes 60

is of comparatively little moment in the standard accordion. In my invention, to secure the advantages of my transposing mechanism, this relationship is of great importance. It is essential to secure an effective transposition of key that the set-up between the player-keys, the actuating levers, the valves and the reeds covered thereby be exactly as shown in Figures 1, 3 and 4.

10 To illustrate what I mean, I take one complete scale with its proper half-notes for illustration, it being understood that the same rule applies to the whole key-operated mechanism and the octaves covered by it. The white player-key C natural shown in the center of the key-board connects directly through the lever and companion valve 19 with the reed-set of 4 reeds nearest to the keyboard. The black key C sharp next to it connects directly with the reed-set of 4 reeds farthest from the keyboard. The white key D natural connects with the set nearest the key board, the black key D sharp with the set farthest from the key board, the white key E natural with the set nearest the keyboard; the white key F natural with the set farthest from the key-board; the black key F sharp with the set nearest the key-board; the white key G natural with the set farthest from the keyboard; the black key G sharp with the set nearest the key-board; the white key A natural with the set farthest from the keyboard; the black key A sharp with the set nearest the keyboard; the white key B natural with the set farthest from the key-board and the white key C natural, which completes the full octave, connects directly with the set nearest to the keyboard. No other arrangement will permit the correct production of tone when my transposing device is operated.

40 To insure at all times correct tone production and prevent the player keys at either end of the keyboard failing to produce the proper note, I add to each of my reed blocks as previously described, the additional reeds 18^a, 18^b giving the next whole tone lower or higher as the case requires.

45 Thus normally, A natural, indicated by the playing key 11^a, is the highest note on the key board and the corresponding endmost reeds 18 are actuated by it and the companion valve 19. When the reed frame unit is adjusted to the right, viewing Figure 3, through the medium of the adjusting screw 26, the adjoining extra reeds 18^b are brought into register with the companion openings 16, 17 and valve 19 associated with said playing key 11^a to thereby effect the proper or desired transposition. When the reed unit is adjusted to the left, the extra reeds 18^a at the right hand end of the reed blocks register with the companion end-most openings and valve 19 and thereby the desired transposition for such adjustment is effected. By adjusting the screw 26 so that the indicator registers with, say No. 1 on the dial 29, the instrument will play in the natural key; by adjusting the screw so that the indicator registers with No. 2 on the dial, the reed blocks will be accordingly shifted and the instrument will play, say in the key of D; and when the indicator is turned to register with No. 3 on the dial, the reed blocks will be shifted in the reverse direction and the instrument will play, say in the key of B flat.

70 It is understood that the letters A, A sharp,

G, G sharp, etc., indicating corresponding musical notes, shown on the playing keys, are only placed thereon for clarity.

I claim as my invention:

1. An accordion, comprising a case having a key-board section and a reed-block section, a plurality of reed blocks arranged within said reed-block section for unitary transposing adjustment lengthwise thereof, each block having openings therein and companion reeds, key-operated valves connected to the respective keys of the key-board for controlling the reeds, each of the reed blocks having companion reeds and openings corresponding in number to the keys and control valves and additional reeds and openings at the opposite ends thereof adapted to be rendered operable in predetermined adjusted positions of the blocks, guides for the reed blocks adjacent opposite ends of said case, the yokes connecting said blocks as a unit and engaging said guide means, one of said tie yokes being disposed at one end of the reed blocks and the other yoke being disposed adjacent the opposite end of the reed blocks, an adjusting screw supported in one end of said case and in threaded connection with the adjoining tie yoke for adjusting the reed blocks lengthwise of said case and relative to said valves, a dial applied to the screw-supporting end of the case, and a pointer connected to the screw to turn therewith in traversing relation to said dial.

2. An accordion, comprising a case having a key-board, reed blocks disposed in longitudinal rows side by side longitudinally of the key-board and guided on said case for unitary transposing adjustment lengthwise thereof, key-operated control valves connected to the respective keys of the key-board for controlling the reeds of said rows of reed blocks, the note keys C, D, E, F#, G# and A# of each octave-scale being connected to the companion successive valves in one row of reed blocks and the alternate note keys C#, D#, F, G, A and B of each octave-scale being connected to the companion successive valves in the other row of reed blocks, and means operatively connected to said reed blocks for adjusting them as a unit in opposite directions relative to said valves to effect the desired transposition.

3. An accordion, comprising a case having a key-board, reed blocks disposed in longitudinal rows side by side longitudinally of the key-board and guided on said case for unitary transposing adjustment lengthwise thereof, key-operated control valves connected to the respective keys of the key-board for controlling the reeds of said rows of reed blocks, each of said reed blocks having a series of reeds corresponding in number to the control valves and additional reeds at the opposite ends thereof rendered operative in predetermined adjusted transposed positions of the blocks, the note keys C, D, E, F#, G# and A# of each octave-scale being connected to the companion successive valves in one row of reed blocks and the alternate note keys C#, D#, F, G, A and B of each octave-scale being connected to the companion successive valves in the other row of reed blocks, and means operatively connected to said reed blocks for adjusting them as a unit in opposite directions relative to said valves to effect the desired transposition.
